(57) **CLAIM**

(22) Filed: **Jan. 12, 2006**

The ornamental design for an anti-asphyxia valve clip for a
respiratory mask, as shown and described.

(51) **LOC (8) Cl. 29-02**

DESCRIPTION

(52) **U.S. Cl. D24/110.1; D24/110.5**

FIG. 1 is a front perspective view of an anti-asphyxia valve
clip for a respiratory mask according to our design;

(58) **Field of Classification Search** D24/110.1,

FIG. 2 is a front view thereof;

D24/110.2–5, 129; D29/102, 110, 122; 2/8,

FIG. 3 is a rear view thereof;

2/9, 424; 128/205.25, 206.21, 206.26, 206.27,

FIG. 4 is a left side view thereof;

128/207.11, 207.13, 207.17

FIG. 5 is a right side view thereof;

See application file for complete search history.

FIG. 6 is a top view thereof;

(56) **References Cited**

FIG. 7 is a bottom view thereof; and,

U.S. PATENT DOCUMENTS

FIG. 8 is a rear perspective view.
